[57] CLAIM

The ornamental design for a storage case for tape cartridges, as shown and described.

DESCRIPTION

FIG. 1 is a front perspective view of a storage case for tape cartridges showing my new design;

FIG. 2 is a top plan view thereof;

FIG. 3 is a front elevational view thereof;

FIG. 4 is a bottom plan view thereof;

FIG. 5 is a right side elevational view thereof;

FIG. 6 is a left side elevational view thereof;

FIG. 7 is a rear elevational view thereof; and

FIG. 8 is a front elevational view with the lid in open position for convenience of illustration.
